UNITED STATES PATENT OFFICE.

CHARLES S. LOCKWOOD, OF NEWARK, NEW JERSEY, ASSIGNOR TO HYATT ROLLER BEARING COMPANY, OF HARRISON, NEW JERSEY, A CORPORATION OF NEW JERSEY.

ROLL-CAGE FOR CLOSED JOURNAL-BOXES.

964,285.

Specification of Letters Patent. Patented July 12, 1910.

Application filed May 19, 1909. Serial No. 497,090.

To all whom it may concern:

Be it known that I, CHARLES S. LOCKWOOD, a citizen of the United States, residing at 289 Market street, Newark, county of Essex, 5 and State of New Jersey, have invented certain new and useful Improvements in Roll-Cages for Closed Journal-Boxes, fully described and represented in the following specification and the accompanying drawings, forming a part of the same.

This invention relates to that class of roller bearings in which the casing is provided with heads or flanges at the opposite ends which cover the ends of the rolls, and 15 necessitate the insertion of the rolls separately through the central aperture or shaft-opening in which the shaft revolves when the bearing is in operation.

The object of the invention is to furnish a 20 so-called roll-guide which may be conveniently inserted through the shaft-opening, and the rolls subsequently inserted into contact with the guide which operates to hold them in parallelism when rotating with them 25 around the shaft. Such roll-guides are very common, but none have heretofore been made of such character that it could be readily inserted through the shaft-opening and operate effectively in connection with a 30 series of loose rolls.

The invention consists of a skeleton frame having tie-bars upon its longitudinal edges and segmental heads *g* at its opposite ends suitably curved to fit within the periphery 35 of the casing, while the tie-bars are disposed at a suitable distance apart to embrace a given number of the rolls.

The invention will be understood by reference to the annexed drawing, in which—

40 Figure 1 is a cross section of the casing with one of the roll-guides inserted, another partly inserted, and dotted lines showing the position for the last guide when fully inserted. Fig. 2 is a section on line 2—2 in 45 Fig. 1; Fig. 3 is a section similar to Fig. 1 with the two guides and the rolls fully inserted; Fig. 4 is an end view of the casing with a hinged guide represented in the central aperture; and Fig. 5 is an end view of 50 the casing and rolls shown in Fig. 3. Fig. 6 shows a one-bar guide.

a designates the cylindrical casing with cylindrical seat *b* to support the rolls.

c are the flanges shown integral with the

ends of the casing and formed each with the 55 aperture *d* for the passage of the shaft.

f designate the rolls, of which twelve are shown in Fig. 3, within the casing, and proportioned to leave space for four guide-bars *e*. 60

The guide-bars are shown connected in pairs with the ends of segments *g*, which are suitably curved to fit within the periphery of the casing, as indicated in Fig. 3, and are of sufficiently limited length to pass 65 through the aperture *d*, as shown in Figs. 1 and 2, where one of the guides is shown in the aperture and extended partly inside the casing. The roll-guide is thus a mere rectangular skeleton frame adapted to embrace 70 loose rolls with the bars *e* fitted radially between the rolls, and set at such a distance apart as to just embrace a given number, as two or three, of the rolls. As the segmental heads *g* occupy a certain space between the 75 flanges *c*, the rolls which lie between the tie-bars *e* are made shorter than the rolls which are not embraced by the guide, and rolls of two different lengths are therefore required to form the series within the casing. 80

To prepare such a roller bearing for the application of the shaft, one of the roll-guides is first inserted through the aperture *d* and dropped to the bottom of the casing, as shown in Fig. 1. Two of the rolls of suitable length to fit between the segments *g* are then dropped within the guide, and an additional roll inserted between them, pushing them laterally against the tie-bars *e*, as shown at the bottom of Fig. 1. Two rolls 85 of suitable length to fit between the flanges *c* may then be placed within each side of the casing, and a second roll-guide inserted and pushed upwardly to the position indicated by dotted lines in Fig. 1. An additional roll may then be crowded between the rolls at opposite sides of the casing, forcing one of each pair against the upper roll-guide, as shown in Fig. 3. Two rolls may 90 then be inserted in the upper guide and an additional roll forced between them, thus supplying the entire twelve rolls to the bearing in connection with the two guides having four guide-bars. To hold the rolls in 95 place while such a bearing may be in transportation, or just before its application to the end of a shaft, a wooden plug of the same size as the shaft may be inserted as 100 105

indicated by the circle h in Fig. 5, and serve to hold the rolls in place while the shaft is inserted, and until the shaft pushes the plug entirely from the casing.

- 5 With the proportions shown in Fig. 3, each of the roll-guides embraces one-quarter of the casing and carries within it one-quarter of the rolls, but the guides may be made to carry one-fifth of the rolls or one-sixth, or any other proportion which may be required to make the guides small enough to enter the casing throughout the aperture d .
- 10 Having thus set forth the nature of the invention what is claimed herein is:

- 15 1. The combination, with a roller bearing casing having flanges upon the ends adapted to wholly cover the rolls, at least one of such flanges having a central aperture for the passage of the shaft, of a rectangular skeleton roll-guide proportioned to pass through the shaft-aperture into the casing, and loose rolls adapted to fit loosely within such rectangular roll-guides.

- 20 2. The combination, with a roller bearing casing having integral flanges upon its ends

adapted to wholly cover the ends of the rolls, and having central apertures for the passage of the shaft, of a series of roll-guides having segmental heads at the ends and tie-bars upon their longitudinal edges and proportioned to pass through the shaft-aperture into the casing, and loose rolls adapted to fit loosely in the space between the heads and side-bars of the guides.

3. The combination, with a roller bearing casing having a central shaft aperture and flanges around such aperture to cover the ends of the rolls, of a rectangular skeleton roll-guide proportioned to pass through the shaft-aperture into the casing, and having at its longitudinal edges radial tie-bars and the outer edges of such tie-bars beveled off to clear the periphery of the shaft opening.

In testimony wherof I have hereunto set my hand in the presence of two subscribing witnesses.

CHARLES S. LOCKWOOD.
